ELECTRIC FITTING

Filed Feb. 6, 1930

INVENTOR.
Leon B. Manson
BY
Zofoni Finckstein
ATTORNEY

UNITED STATES PATENT OFFICE

LEON B. MANSON, OF CORONA, NEW YORK, ASSIGNORS TO NOMA ELECTRIC CORPORATION, OF NEW YORK, N. Y., A CORPORATION OF NEW YORK

ELECTRIC FITTING

Application filed February 6, 1930. Serial No. 426,239.

This invention relates to electric fittings.

An object of this invention is to provide a fitting of the character described having improved quickly replaceable fuse cartridge means interposed in the current carrying portions of the fitting.

A further object of this invention is to provide a fitting of the character described having improved means for removably mounting all the current carrying portions of the fitting as a single unit within a single housing.

A still further object of this invention is to provide a neat, compact and rugged device of the character described, which shall be comparatively inexpensive to manufacture, comprise few and simple parts, easy to assemble and replace, and which shall yet be practical and efficient to a high degree.

Other objects of this invention will in part be obvious and in part hereinafter pointed out.

The invention accordingly consists in the features or construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is an axial cross-sectional view of the fitting embodying the invention;

Fig. 2 is a cross-sectional view taken on line 2—2 of Fig. 1;

Fig. 3 is a cross-sectional view taken on line 3—3 of Fig. 2; and

Fig. 4 is a perspective view of the removable unit mounting the current carrying portions of the fitting.

Referring now in detail to the drawings, 10 designates an electric fitting embodying the invention here shown in the form of a two-piece plug, comprising a screw plug 11 provided with the usual parallel openings 12 for receiving the contact members or blades 14 and 15 of a blade plug 16.

The plug 16 comprises a tubular housing 17 made of any suitable insulating material 50 preferably open at one end 18 and having a

rear end wall 19 formed with a central opening 20. A cylindrical portion of the interior cylindrical surface of said housing 17 is threaded as at 21 for the purpose hereinafter described.

In accordance with this invention, all of the current carrying parts for the plug 16 are mounted on a single block and form a unitary device adapted for removable attachment, in the manner hereinafter appearing, 60 as a single complete unit within the housing 17. Said unit, designated by the reference numeral 25, comprises the block 26 made of insulating material and provided with threaded portions 27 and 28 at the ends thereof adapted to cooperate with the internal threads 21 of the housing 17. Thus, when the block 26 is screwed to the threaded portion 21 of the housing as shown in Fig. 1, the former forms a diametric, longitudinal partition or wall across the interior of said housing and provides space on both sides thereof and at the rear and front thereof, for the purpose hereinafter described. Said block may be provided with a pair of symmetrical recesses or cut out portions 30 and 31 at the ends of the rear surface thereof and with symmetrical recesses 32 and 33 at the ends of the front surface thereof. Attached to said block 26 are a pair of symmetrical angular shaped, rearwardly extending metal current carrying terminal members 35 and 36 having legs 35a and 36a, respectively, disposed within the recesses 30 and 31. Screws 37 and 38 passing thru suitable openings in 85 legs 35a and 36a, respectively, serve to fix said members 35 and 36 to the block. The outwardly extending legs 35b and 36b of members 35 and 36 respectively, are formed with suitable openings for receiving small 90 screws 40 and 41 for attaching the conductors 40a and 41a of a duplex cable 42 to the fitting. It will be noted that the cable 42 extends into the housing 17 thru the opening 20 in the rear wall 19. Attached to the 95 opposite side of the block are the plug blades 14 and 15, as by screws 44 and 45 extending thru legs 14a and 15a of said blades, said legs being received in the cut out portions 32 and 33 respectively of said block.

Said unit 25 is furthermore provided with quickly replaceable fuse means 50 on one side of the block, interconnecting the plug blade 15 with current carrying member 35 and fuse means 51 on the other side of said block, interconnecting the plug blade 14 with the current carrying member 36. Said means 50 and 51 are substantially similar in construction and symmetrically disposed with respect to 10 one another. Means 50 comprises a thin metallic bent strip 52 having an arm 53 interposed between said leg 35a and the insulating block 26, a portion 53a lying flat against a side of the block, and a pair of bifurcated 15 spring clamping arms 54 extending at right angles to said block. A member 52a similar in construction to said member 52 is electrically connected to the plug blade 15 and is likewise provided with a portion interposed 20 between the leg 15a of said blade and the insulating block 26, a portion lying flat against the side wall of the block and a pair of spring arms aligned with said spring arms 54. A fuse cartridge 55 provided with metal caps 25 at the ends thereof is removably attached to the unit 25 as by pressing said caps into engagement with the spring arms of said members 52, 52a. The fuse means 51 is likewise provided with metallic bent strip members 30 connected to the member 36 and the plug blade 14 on the opposite side of the block and is also provided with a removable fuse cartridge 52a similarly clamped and frictionally retained against the side of said block 26. 35 In practice, the blade unit 25 may be first assembled into a separate compact device. To assemble the plug 16, the conductor cable 42 is first inserted thru the opening 30 and attached to the screw members 40 and 41 and 40 the block 26 thereafter screwed to the interior of the housing. Should one or both of the fuses blow the entire unit 25 may easily be removed by unscrewing from the housing 17 and the burnt out fuses replaced. An 45 insulating disc or plate 60 having openings 61 for receiving the blades 14 and 15 may be interposed between the plugs 11 and 16, said disc preferably extending within the rim of the housing 17 at the end 18 thereof. 50 It will be noted that the fuse cartridges 55 and 55a are disposed on both sides of the block 26 and extend laterally with respect to the axis of housing 17, thus making for a compact construction. Said cartridges are 55 hence furthermore completely housed and protected by said housing to prevent tampering or accidental unloosening of said cartridges, and the current carrying portions are well insulated to prevent short circuits 60 within the plug.

It will thus be seen that there is provided a device in which the several objects of this invention are achieved, and which is well adapted to meet the conditions of practical 65 use.

As various possible embodiments might be made of the above invention, and as various changes might be made in the embodiment set forth, it is to be understood that all matter herein set forth or shown in the accompanying drawings, is to be interpreted as 70 illustrative and not in a limiting sense.

Having thus described my invention, I claim as new and desire to secure by Letters Patent:

1. An electric fitting comprising a hollow housing made of insulating material and having an internally screw threaded portion, a member made of insulating material and of substantially prismatic shape and having partial screw threads on opposite ends thereof adapted to co-operate with said screw threaded portion for mounting said member within said housing and current carrying parts for said fitting mounted on said member, whereby all of the current carrying parts may be removed as a unit from said housing. 85

2. A plug comprising a tubular housing having a rear wall formed with an opening, an insulating member removably secured within said housing, a pair of terminal members fixed to the rear of said member, a pair of plug blades fixed to the front of said member, fuses interconnecting said blades with said terminal members and a conductor extending into said housing thru said opening and secured to said terminal members. 90

3. An electric fitting comprising a tubular housing, a substantially prismatic insulating member removably secured within said housing and diametrically disposed therein, and a fuse cartridge removably mounted on each side of said member. 100

4. An electric fitting comprising a tubular housing, an insulating member removably secured within said housing and diametrically disposed therein, and a fuse cartridge removably mounted on each side of said member, said cartridges being disposed transversely with respect to the longitudinal axis of said housing. 105

5. An electric fitting comprising a tubular insulating housing having an end wall and being formed with an internal screw threaded portion, a substantially prismatic block made of insulating material adapted to cooperate with said portion for removably securing said block within said housing, said block forming a longitudinal, diametric partition across said housing and current carrying parts for said fitting mounted on said member. 115

6. An electric fitting comprising a tubular insulating housing having an internal screw threaded portion, a member made of insulating material adapted to cooperate with said portion for removably securing said member within said housing, said member forming a longitudinal partition within said hous- 125

ing, and current carrying parts for said fitting mounted on said member, said parts including a cartridge fuse disposed within said housing transversely of the longitudinal axis of said housing.

7. An electric fitting comprising a tubular insulating housing having an internal screw threaded portion, a member made of insulating material adapted to cooperate with said portion for removably securing said member within said housing, said member forming a longitudinal partition within said housing and current carrying parts for said fitting mounted on said member, said parts including a cartridge fuse disposed within said housing transversely of the longitudinal axis of said housing, and removably mounted on said member.

8. An electric fitting comprising a tubular insulating housing, a substantially prismatic insulating block removably secured within said housing and forming a longitudinal diametric wall across the interior of said housing, a contact member fixed to said block adjacent one end thereof and extending forwardly, a terminal member secured to said block at the opposite end thereof and extending rearwardly, a fuse cartridge, and spring friction means connected to said contact member and terminal for removably mounting said fuse on said insulating block.

9. An electric fitting comprising a tubular insulating housing having an internally screw threaded portion, a substantially flat insulating member having partial threads at the ends thereof adapted to co-operate with said internally screw threaded portion whereby said member forms a diametric partition across the interior of said housing, a pair of plug blades attached to the front of said insulating member adjacent the ends thereof and extending upwardly therefrom, a pair of terminal members secured to the rear of said insulating member adjacent the ends thereof and extending rearwardly therefrom, and a pair of fuse members disposed on opposite sides of said partition member, each interconnecting a blade adjacent one end of said insulating member with a terminal member adjacent the opposite end of said insulating member.

10. An electric fitting comprising a tubular insulating housing having an internally screw threaded portion, a substantially flat insulating member having partial threads at the end thereof adapted to co-operate with said internally screw threaded portion whereby said member forms a diametric partition across the interior of said housing, a pair of plug blades attached to the front of said insulating member adjacent the ends thereof and extending forwardly therefrom, a pair of terminal members secured to the rear of said insulating member adjacent the ends thereof and extending rearwardly there-

from, and a pair of fuse members disposed on opposite sides of said insulating member, each interconnecting a blade adjacent one end of said insulating member with a terminal member adjacent the opposite end of said insulating member, said tubular housing having an end wall at the rear thereof, said end wall being formed with an opening, and a pair of conductor wires extending through said opening and connected to said terminal members.

In testimony whereof I affix my signature.
LEON B. MANSON.
